[57] **CLAIM**

The ornamental design for a children's computer key-

board with large colorful alphabetically arranged keys, as shown and described.

DESCRIPTION

FIG. 1 is an isometric drawing showing my new design for a children's computer keyboard with large colorful alphabetically arranged keys, equally large numerical keys, and large diamond-shaped cursor keys;

FIG. 2 is an inverted rear elevational view of my invented design for a children's computer keyboard with large colorful alphabetically arranged keys;

FIG. 3 is a top view of the invented children's computer keyboard with large colorful alphabetically arranged keys;

FIG. 4 is a left side view of the invented keyboard of FIG. 3;

FIG. 5 is a right side view of the invented keyboard of FIG. 3;

FIG. 6 is a front elevational view of the invented keyboard of FIG. 3;

FIG. 7 is a bottom view of the invented keyboard of FIG. 3 with the legs in the closed position;

FIG. 8 is a bottom view of the invented keyboard of FIG. 3 with the legs in the extended position;

FIG. 9 is a left side view of the invented keyboard of FIG. 3 with the legs in the extended position;

FIG. 10 is a right side view of the invented keyboard of FIG. 3 with the legs in the extended position; and,

FIG. 11 is a rear view of the invented keyboard of FIG. 3 with the legs in the extended position.
